UNITED STATES PATENT OFFICE.

JOHN R. MCGIFFERT, OF DULUTH, MINNESOTA, ASSIGNOR TO CLYDE IRON WORKS, OF DULUTH, MINNESOTA, A CORPORATION OF MAINE.

TROLLEY-CARRIAGE.

1,286,688.

Specification of Letters Patent.

Patented Dec. 3, 1918.

Application filed January 12, 1915. Serial No. 1,774.

To all whom it may concern:

Be it known that I, JOHN R. MCGIFFERT, a citizen of the United States, and a resident of Duluth, county of St. Louis, and State 5 of Minnesota, have invented a new and useful Improvement in Trolley-Carriages, of which the following is a specification, the principle of the invention being herein explained and the best mode in which I have 10 contemplated applying that principle, so as to distinguish it from other inventions.

The present invention relates to a trolley carriage for use with an overhead cableway and is designed to provide a mechanism 15 which will eliminate much of the wear which at present falls upon the various elements of such a device. To the accomplishment of the foregoing and related ends, said invention, then, consists of the means hereinafter fully described and particularly 20 pointed out in the claims.

The annexed drawings and the following description set forth in detail certain mechanism embodying the invention, such disclosed means constituting, however, but one 25 of various mechanical forms in which the principle of the invention may be used.

In said annexed drawings:—

Figure 1 is a side elevation showing my 30 improved carriage in connection with an overhead cableway; Fig. 2 is an enlarged side view of the carriage alone; Fig. 3 is an end view of the carriage looking from the right in Fig. 2, and Figs. 4 and 5 are side elevations of the main sheave and the ratchet disk, respectively, showing adjacent sides of the same when in operative relation.

In Fig. 1 there is shown the usual trolley cable 1 upon which is mounted the trolley carriage comprising spaced plates 3 and 4, held in such relation by any suitable means. At the upper corners of the frame of the carriage there are mounted small sheaves or rollers 5 and 6, which support the carriage upon the trolley cable. Centrally mounted in the frame upon a pin 7 is the main sheave 8 about which a skidding cable 43 is passed several times, such cable then depending from the sheave and being 40 provided at its outer end with chokers 10 for attachment to a log. In case the device is used for other than logging purposes, other suitable engaging elements will be used on the end of the skidding cable. The 45 sheave 8 is provided with a plurality of

spaced peripheral notches 11 and such notches are adapted to be engaged by a pivoted pawl or latch 12 which is actuated into such engagement by means of a spring 13. When the pawl 12 is in engagement with 50 one of the notches 11 in this sheave 8, this sheave is restrained from what may be termed "unwinding rotation," that is rotation in a clock-wise direction, as the sheave is viewed in the several figures. Mounted 55 concentrically with the sheave 8 is a disk 14 which is also provided with a plurality of notches 15 which in position and size are similar to the notches 11 in the sheave. This disk is provided with a slot 16 in which a 60 tongue 17 of the sheave is engaged, the tongue being smaller than the slot thus giving the disk a certain rotating capacity with respect to the sheave. When the sheave is turned in the clock-wise direction the tongue 65 70 engages the left side of the slot and the notches in the disk and sheave are then in register and may be engaged by the pawl to prevent unwinding rotation of the sheave. When the sheave is moved in a counter 75 80 clock-wise direction it leaves the disk behind during the first movement and the notches are then brought out of register and a continuous periphery is presented to the pawl so that the latter does not drop down 85 into each notch as the sheave is rotated.

Attached to a clevis 20 mounted in the front side of the frame is an outhaul cable 21 which passes over a suitable sheave at the forward end of the trolley cable and is then 90 brought back to a winding drum 40. Pivotally mounted between the plates at the rear of the frame is an arm or member 25 provided with a plurality of holes 26 and this plate is connected by means of rods 27 95 with ears 28 which extend downward from the pawl 12. In one of the apertures on the plate there is attached the outer end of the buggy cable 41 which passes back to a winding drum 42. A skidding cable 43 is provided and is wound upon, and operated by a drum 50. It will be understood that the drums 40, 42, and 50 represent diagrammatically the drums usually placed upon a car or base and may be operated by any desired 100 means.

Mounted above the arm 25 is a small sheave 30 adapted to guide the skidding cable 43 on to the main sheave 8. On the lower edge of each plate of the frame there 110

is attached a liner or strip 44, and between the ends of these two liners there are rotatably mounted small rollers 45 which are for the purpose of preventing contact between the skidding cable and the sharp edges of the frame in case the skidding cable is moved to an abnormal backward or forward position.

From the foregoing description the construction of the mechanism will be clear. The operation is as follows.

When the trolley carriage is mounted upon the inner end of the trolley cable 1 the outhaul cable 21 is wound in, causing the carriage to recede and thus drawing out with it the skidding cable 43 and the buggy cable 41. The carriage is run somewhat beyond the point at which the load is to be picked up, in order to secure the desired amount of slack in the skidding cable, which is accomplished by hauling in the carriage with the buggy line until it is over the load. When the buggy cable is thus actuated to draw back the carriage it disengages the pawl 12 and thus permits unwinding rotation of the main sheave so that the skidding cable may now be drawn out by the operators and attached to the load. It is necessary to maintain this tension on the buggy cable in order to prevent the weight of the outhaul cable from acting on the carriage to move the same outward, which would take up part of the slack on the skidding line. When the skidding cable has been secured to the load, the buggy cable is released and the skidding line is then drawn in, the outhaul cable being held taut by means of a brake until the load is raised to the desired height. As soon as the tension of the buggy cable is released, the pawl is again actuated to engage the notches in the sheave and accordingly when the skidding line has been drawn in and the load raised, the pawl will engage the notches in the sheave. The outhaul cable is now released and the carriage is hauled in by pulling on the skidding cable. At the same time the buggy cable is drawn in at the same speed as the skidding cable, although allowed to run slack without taking up the load. In order to lower the logs the drum 40 operating the outhaul cable 21 is held against movement by a brake, here illustrated diagrammatically at 51, thus preventing further movement of the carriage. The drums 42 and 50 continue their winding, however, thus slightly elevating the load and taking the pressure off the latch or dog 12 which is simultaneously disengaged by the pull on cable 41. The load may then be lowered.

One important advantage of my invention is its safety of operation. In many cases this type of a carriage is used in mountain work in handling logs down a slope. In 65 many of the carriages now used the load is

locked to the carriage and if the outhaul cable breaks, the carriage and load will run down the trolley with, of course, great danger to the machine and the men at the lower end of the cableway. In my improved carriage, however, the breaking of the outhaul cable merely permits the carriage to move faster than the rate of winding of the skidding cable, permitting this cable to slacken and thus slip around the sheave with the result that the load falls to the ground.

By the present mechanism the load on the running cables and the power required, are much reduced although the operating effectiveness is increased.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a trolley carriage, the combination with a frame and supporting rollers therefor, a sheave mounted in said frame and adapted to movably support a skidding cable passing thereover, of means adapted to prevent unwinding rotation of said sheave, said means including a member mounted rotatably and concentrically with said sheave, and a latch adapted to engage with said member and said sheave when in a predetermined relation.

2. In a trolley carriage, the combination with a frame and supporting rollers therefor, a sheave mounted in said frame and adapted to movably support a skidding cable passing thereover, a circular member mounted rotatably and concentrically with said sheave, said sheave and said member having equally spaced peripheral notches, and a latch member adapted to engage in notches in said sheave and member when such notches are in register.

3. In a trolley carriage, the combination with a frame and supporting rollers therefor, a sheave mounted in said frame and adapted to movably support a skidding cable passing thereover, a circular member mounted rotatably and concentrically with said sheave, said sheave and said member having equally spaced peripheral notches, a pivoted latch member adapted to be normally pressed against the notched surfaces of said sheave and said member and to engage in such notches when in register, and a buggy line attached to said latch and adapted to disengage the same from such notches when placed under a predetermined tension.

4. In a trolley carriage, the combination with a frame and supporting rollers therefor, a sheave mounted in said frame and

provided with peripheral notches, a disk mounted adjacent to said sheave and provided with similar peripheral notches, said disk being slightly rotatable with respect to 5 said sheave, and an outhaul cable attached to said frame, and a skidding cable wound about said sheave, of a pawl adapted to engage the notches in said disk and said sheave when the same are in register and to thereby 10 prevent unwinding rotation of said sheave, a plate pivotally attached to said frame, connections between said pawl and said plate and a buggy line attached to said plate and adapted to actuate the same when placed 15 under tension.

5. In a trolley carriage, the combination with a frame and supporting rollers therefor, a sheave mounted in said frame and provided with peripheral notches, a disk 20 mounted adjacent to said sheave and provided with similar peripheral notches, said

disk being slightly rotatable with respect to said sheave, and an outhaul cable attached to said frame, and a skidding cable wound about said sheave, of a pawl adapted to engage such notches of said disk and sheave when the same are in register, resilient means 25 normally maintaining said pawl in such engagement, a plate pivotally attached to said frame connections between said plate and 30 said pawl, and a buggy line attached to said plate in position to actuate the same and thereby release said pawl when said line is placed under tension greater than the tension of said resilient means. 35

Signed by me, this 9th day of January, 1915.

JOHN R. McGIFFERT.
